UNITED STATES PATENT OFFICE.

CONRAD MILLER, OF DENVER, COLORADO.

DUMPING-BODY FOR VEHICLES.

No. 847,964.

Specification of Letters Patent.

Patented March 19, 1907.

Application filed May 11, 1904. Serial No. 207,497.

To all whom it may concern:

Be it known that I, CONRAD MILLER, a citizen of the United States of America, residing in the city and county of Denver and State of Colorado, have invented certain new and useful Improvements in Dumping-Bodies for Vehicles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in dumping-bodies for vehicles. The end portions of my improved wagon-body have bottoms downwardly inclined from their outer extremities, while the space between these two inclined bottom portions is normally closed by a tiltable chute, either extremity of which is adapted to be lowered to allow the entire contents of the wagon-body to be discharged therefrom on either side, as may be desired. Each extremity of the tiltable chute projects a short distance from the sides of the wagon-body on each side and with it is connected suitable attachments whereby either extremity of the chute may be locked in the raised position or released and allowed to fall to the dumping position, as circumstances may require. When this tiltable chute is in the raised or elevated position, it forms the central part of the wagon-body bottom and co-operates with the inclined ends of the bottom to form the complete bottom of the wagon-body. These inclined ends are hinged and adapted to be lowered to the horizontal position or to a position in the plane of the central part of the wagon-body bottom when the latter is raised. When the inclined bottom end portions are lowered or when either of them is lowered, the contents of the wagon-body may be shoveled out of it in the ordinary way when it is not desired to dump the contents of the wagon-body by moving the tiltable chute to the inclined position.

Having briefly outlined my improved construction, as well as the function it is intended to perform, I will proceed to describe the same in detail, reference being made to the accompanying drawing, in which is illustrated an embodiment thereof.

In the drawing, Figure 1 is a side elevation of my improved dumping wagon-body, the

tiltable chute being lowered to the dumping position. Fig. 2 is a similar view with the chute raised to the closed position. Fig. 3 is a vertical longitudinal section taken through the wagon-body. Fig. 4 is a vertical cross-section taken on the line 4-4, Fig. 1. Fig. 5 is an underneath view of one of the hinged end sections of the wagon-body bottom, illustrating the means for locking it in the raised or inclined position.

The same reference characters indicate the same parts in all the views.

Let A designate the opposite vertical sides of the wagon-body, whose bottom is composed of two end parts (each designated A') and a central part, (designated A²). These end parts normally occupy an inclined position, as shown at the right of Fig. 3; but they are hinged at their lower extremities, as shown at A³, and are adapted to be locked in the inclined position by means of a lever B fulcrumed on the under side of the part A', as shown at B'. Pivotedly connected with the lever at points B² on opposite sides of its fulcrum are two locking-rods B³, which engage guides B⁴, having ways which register with recesses B⁵, formed in the opposite sides of the wagon-body and adapted to receive the outer extremities of the rods B³ when the lever is shifted to the position shown in Fig. 5. When, however, it is desired to lower the bottom section A' to the position shown at the left in Fig. 3, the lever B is shifted to the reverse position, or rather to a position causing its inner extremity to engage a stoppin B⁶, when the locking rods or pins B³ will be moved inwardly sufficiently to disengage them from the recesses of the wagon-body sides, whereby the part A' may be lowered to the horizontal position, as shown at the left in Fig. 3. It may be assumed, however, that both of the bottom sections A' are in the inclined position, as it is supposed that the wagon-body will be used more with the said sections in the inclined position than in any other way, since it is more especially intended as a dumping-body, whereby as the chute A², forming the central part of the bottom, is lowered at either end the entire contents of the body may be allowed to escape at the side as heretofore explained.

The manner of operating the tiltable chute A² will now be described in detail. This chute forms the central portion of the wagon-body bottom, as heretofore explained, and is adapted to close the central opening between

the two inclined parts A' of said bottom. This chute or central wagon-body bottom section is suspended at opposite sides of the wagon-body by means of chains D, two on each side. The lower extremities of the chains are connected with hooks D', movably attached to eyes D², secured to the chute just outside of the vertical sides of the wagon-body. The upper extremities of the two chains on each side of the wagon-body are connected with levers E and F, respectively. These levers are provided with curved or segmental portions E' and F', respectively, whose peripheries are grooved to receive the chains, the latter being attached to the upper extremities of the said segmental parts of the levers. The two levers are so located that there is constantly a vertical upward pull on the chains, whereby the latter are kept in a perpendicular position during the operation of raising and lowering the chute, thus preventing any tendency toward side strain or friction on the chute. The levers E and F are connected at points E² and F², respectively, by a connecting-rod G. The lever F is provided with an extension F³ above or beyond a point F², and this extension is connected, as shown at H, with one extremity of a rod H', whose opposite extremity is connected, as shown at H², with a hand-lever H³, provided with a locking-pawl H⁴, engaging a quadrant H⁵. This lever is fulcrumed at its lower extremity, as shown at H⁶, and the dog H⁴ is controlled by means of a pivot-ed handpiece H⁷, pivotally connected with the lever. This part H⁷ is connected with the dog H⁴ by a rod H⁸. This is an ordinary lever and quadrant construction. It will be understood that both sides of the wagon-body are equipped with a set of the devices just explained, and since the operating devices for the tiltable chute are the same on both sides of the wagon a description of the wagon on one side is sufficient.

It will be observed that when the chute A² is lowered at one end, as best illustrated in Fig. 4 of the drawing, the supporting devices connected with the opposite end form, in effect, a hinge, permitting the free upward-and-downward movement of the chute in a manner that will be readily understood. For convenience in dumping or discharging the contents of the wagon-body the chute is provided with end extensions A⁴, having upwardly-extending side pieces composed of metal plates A⁵, extending across the bottoms of the end extensions and having their extremities A⁶ turn upwardly on opposite sides of the said extensions. These upwardly-turned parts prevent the material from falling off from the side of the chute as soon as they leave the wagon-body, and by means of them the material or contents of the wagon-body may be discharged into any convenient receptacle or location. On oppo-

site sides of the chute or central bottom section A² of the wagon-body are located depending parts I, which extend downwardly far enough to prevent the material from passing over the sides of the chute within the vertical planes of the sides of the wagon-body. These parts I also serve as guides for the chute during its upward-and-downward movement.

The ends of the wagon-body are provided with narrow vertical sections J, engaging ways J', formed on opposite sides of the wagon-body. These vertical end sections J rest upon the outer extremities of the inclined hinged sections A' and may be removed as soon as the inclined sections are lowered to the horizontal position. At the extremities of the wagon-body are located cross-pieces K, which form a support for the sections A' when lowered to the horizontal position.

The parts designated L and M in the drawing constitute the rear and front axles of the vehicle, respectively, to which it may be assumed my improved wagon-body is applied. In Figs. 1 and 2 the wheels of the vehicle are indicated by dotted lines.

The wagon-body is provided on opposite sides of the depending parts I with cross-bars N, which give additional strength and durability to the structure.

Attention is called to the fact that the levers E and F are fulcrumed at E³ E³, respectively, while the periphery of the segmental parts E' and F' of the said levers form the arcs of circles struck from the fulcrum-points E³ as centers. This is necessary in order that the point from which each chain pulls may always be directly above the point at which the lower extremity of the chain is connected with the chute, whereby all tendency toward side thrust and friction is overcome.

From the foregoing description the use and operation of my improved dumping-body for vehicles will be readily understood. Assuming that the chute A² is in the closed position, as shown in Figs. 2 and 3 of the drawing, and that the inclined bottom sections A' are in the position shown at the right of Fig. 3 and as indicated by dotted lines in Figs. 1 and 3, if it is desired to dump the contents of the wagon-body the hand-lever H³ on one side is thrown from the position indicated in Fig. 2 to that indicated on the nearest side of Fig. 1, whereby the levers E and F are shifted sufficiently to allow one end of the chute A² to drop downwardly to the dumping position. It will then be understood that the entire contents of the wagon-body may be discharged at the side of the wagon-body, where the protruding extremity of the chute is lowered. It will be understood that while the one extremity of the chute is lowered, as shown in Fig. 1 of

the drawing, and the operating or manipulating devices are correspondingly actuated the said devices connected with the opposite extremity of the chute are retained in their 5 normal or locking position. If it is desired to shovel out the contents of the wagon-body in the ordinary way, the tilttable chute or central part A² of the wagon-body bottom is kept closed and one or both wagon-body 10 parts A' are lowered to the horizontal position, the upper end sections J being one or both removed, as may be desired. When this is done, it is evident that the structure 15 may be used as an ordinary wagon-body.

Though I have shown and described a special lever construction for manipulating the chute A², it must be understood that the invention is not limited to this construction, as other forms of levers may be employed 20 without departing from the spirit of the invention.

Having thus described my invention, what I claim is—

1. A wagon-body whose end portions are 25 provided with inclined bottom sections and whose middle portion between the end sections is composed of a transversely-tilttable central part extending entirely across the wagon-body, levers mounted on the wagon- 30 body, a connection between the levers, and a connection between each lever and the tilttable part whereby the said part may be manipulated at will.

2. A wagon-body whose extremities are 35 provided with bottom sections downwardly inclined toward the center of the wagon-body, the central portion of the wagon-body between the end sections of the bottom, being provided with a tilttable chute which 40 when closed or raised at both ends forms the central part of the wagon-body, two levers mounted on each side of the wagon-body, flexible devices connecting each extremity of the chute with each pair of levers, a link 45 connecting the two levers, a hand-lever connected with one lever of the chute, and a quadrant coöperating with the hand-lever, substantially as described.

3. A wagon-body whose end portions are 50 provided with inclined bottom sections and whose middle portion between the end sections is composed entirely of a transversely-tilttable part, levers mounted on the wagon-body, a connection between the levers, and a 55 connection between each lever and the said tilttable part whereby the said part may be manipulated at will.

4. A wagon-body whose bottom is provided with a centrally-located transversely- 60 tilttable section extending entirely across the wagon-body, levers mounted on the wagon-body, a connection between the levers, and a connection between each lever and the tilttable section whereby the said section may 65 be manipulated at will.

5. A wagon-body whose bottom is provided with a transversely-tilttable section extending entirely across the said body, vertical guides located on opposite sides of the tilttable section, whereby the contents of the 70 wagon-body is prevented from escaping from the chute between the planes of the vertical sides of the wagon-body, levers mounted on the wagon-body, a connection between the levers, and a connection between each lever 75 and the tilttable section whereby the said section may be manipulated at will.

6. A wagon-body whose end portions are provided with inclined bottom sections and whose middle portion between the end sections is provided with a transversely-tilttable part extending entirely across the wagon-body, levers mounted on the wagon-body, a connection between the levers, and a connection between each lever and the tilttable part 80 85 whereby the said part may be manipulated at will.

7. A wagon-body whose end portions are provided with hinged sections adapted to be raised to a suitably-inclined position whereby the contents of the body is adapted to slide toward the central portion of the wagon-body bottom, the said central portion extending entirely across the wagon-body and being transversely tilttable for dumping purposes, 90 levers mounted on the wagon-body, a connection between the levers, and a connection between each lever and the said tilttable portion 95 whereby the said portion may be manipulated at will. 100

8. A wagon-body having a transversely-tilttable section, and levers mounted on the wagon-body, a connection between the levers, and a connection between each lever and the tilttable section whereby the said section 105 may be manipulated at will.

9. A wagon-body provided with a centrally-located transversely-tilttable part, two levers fulcrumed on the wagon-body and connected with the transversely-tilttable section, 110 a connection between the two levers, and a hand-lever connected with one of the first-named levers whereby the tilttable dumping-section may be manipulated for the purpose set forth. 115

10. A wagon-body whose extremities are provided with bottom sections downwardly inclined toward the center of the wagon-body, the central portion of the wagon-body between the end sections of the bottom, being 120 provided with a transversely-tilttable chute which when closed or raised at both ends forms the central part of the wagon-body, two levers mounted on each side of the wagon-body and having grooved segmental parts, 125 each segmental part describing a curve struck from the fulcrum of the lever, and a flexible device connected with the outer grooved edge of each segmental part of each lever and leading to the tilttable chute, a con- 130

nection between each pair of levers on the same side of the wagon-body, and a hand-lever fulcrumed on each side of the wagon-body and connected with one of the chute-manipulating levers for the purpose set forth.

11. A wagon-body provided with a hinged section located at one extremity thereof, and means for supporting the hinged section in an inclined position, comprising a lever fulcrumed on the hinged section, and locking-rods connected with the lever and adapted to enter openings formed in the opposite sides of the wagon-body.

12. A wagon-body provided with end sections hinged at their inner extremities, means for supporting the outer extremities in such a position that the sections will be downwardly inclined in the said outer extremities,

and means connected with each extremity of the wagon-body for supporting the hinged sections in the horizontal position when released from the means for supporting them in the inclined position.

13. A wagon-body provided with inclined end sections, their outer extremities being highest, and removable end-gates located in ways formed at the opposite ends of the wagon-body, the lower edges of the end-gates resting on the outer extremities of the inclined end bottom sections.

In testimony whereof I affix my signature in presence of two witnesses.

CONRAD MILLER.
